(57) **CLAIM**

The ornamental design for a flashlight with an electronic insect repellent, as shown and described.

DESCRIPTION

FIG. 1 is a perspective view of a flashlight with an electronic insect repellent;

FIG. 2 is a front view thereof;

FIG. 3 is a first side view thereof;

FIG. 4 is a rear view thereof;

FIG. 5 is a second side view thereof;

FIG. 6 is a bottom view thereof; and,

FIG. 7 is a top view thereof.

The broken lines shown in the figures show portions of the flashlight that form no part of the claimed design.

1 Claim, 4 Drawing Sheets
